(57) **CLAIM**

The ornamental design for a ceiling fan blade iron, as shown and described.

DESCRIPTION

FIG. 1 is a perspective view of a ceiling fan blade iron showing my new design, shown in an inverted position for clarity of explanation.

FIG. 2 is a right side view thereof.

FIG. 3 is a left side view thereof.

FIG. 4 is a top view thereof.

FIG. 5 is a bottom view thereof.

FIG. 6 is a front view thereof; and,

FIG. 7 is a rear view thereof.

The broken line showing of environmental structure is for illustrative purposes only and forms no part of the claimed design.
